UNITED STATES PATENT OFFICE.

HORACE F. HODGES, OF CHELSEA, ASSIGNOR TO CHARLES F. PAYNE, OF GROVELAND, AND GEORGE H. SPENCER, OF FITCHBURG, MASS.

PUMP.

SPECIFICATION forming part of Letters Patent No. 311,581, dated February 3, 1885.

Application filed September 6, 1883. (No model.)

To all whom it may concern:

Be it known that I, HORACE F. HODGES, a citizen of the United States, residing at Chelsea, in the county of Suffolk and State of Massachusetts, have invented a new and useful Valveless Pump, of which the following is a specification.

My invention relates to that class of pumps whereby liquids are raised by means of a piston working in a cylinder without the use of valves, supplementary pistons being employed in their stead.

It has long been admitted that the chief defect in pumps has been the uncertainty of the action of the valves employed to check the backward flow of the liquid being pumped. A very slight defect in the seating of the valves often destroys the suction, and also impairs the forcing-power of the pump.

In the endeavor to make the valves seat perfectly india-rubber and other materials have been employed, which are liable to be impaired by hot liquids, chemicals, &c., and often cause the valves to give out at very inconvenient times. Liquids containing a sediment and those depositing a hard or gummy substance—such as sirups, oils, &c.—often make it impossible to use the ordinary pump by reason of these deposits adhering to the valves and keeping them from their seats; nor will these valves sustain, without disarrangement, so great a pressure as the other parts of the pump. To overcome these difficulties, I dispense with valves altogether, and substitute therefor two supplementary pistons, one in each end of the cylinder, and connected together preferably by rods which pass through the main piston. These supplementary pistons act as movable cylinder-heads, and by their movement and that of the main piston conduct the water or other fluid from the inlet to the delivery ports. The supplementary pistons can be operated by friction from the main piston, or by a separate piston-rod or sleeve operated independently by a positive motion, the latter being preferable where a heavy suction is required.

Referring to the accompanying drawings, Figure 1 represents a longitudinal vertical section through a pump embodying my invention. Fig. 2 is a section on line $x-x$ of Fig. 1.

Fig. 3 is a section on line $y-y$. Fig. 4 is a section on line $z-z$.

a is the cylinder, cast in one piece with the water chamber *o*.

b b' are the covers for same, one of which is fitted with a stuffing-box, *g*, through which the piston-rod *e* passes. In the center of the length of the cylinder is a suction-port, *l*. At opposite ends of the cylinder are delivery-ports *m m'*, communicating with the water-chamber *o*, from which leads a delivery-pipe, *n*.

c is the main piston, at either end of which is fitted a supplementary piston, *d d'*. These latter are connected together by rods *f f*, which pass through holes in the main piston *c*, so that the latter can move independently of the supplementary pistons *d d'*, the piston-rod *e* passing through a hole in the supplementary piston *d*, and through a sleeve, *p*, which latter is provided with a stuffing-box, *h*.

In the piston *c* are two holes (see Fig. 2) leading to the connecting-rods *f f*, in which holes are inserted friction-blocks *j j*, that are kept pressed against the rods *f f* by means of the springs *i i*, against which rest plugs *k k*, screwed into the outer ends of the holes. By this means I obtain sufficient friction to carry the supplementary pistons with the main piston until one of them comes in contact with the cylinder-cover, when the main piston *c* finishes its stroke while the supplementary pistons are at rest; but upon the piston *c* commencing its return-stroke, the friction of the blocks *j j* upon the rods *f f* will cause the supplementary pistons *d d'* to be carried forward with the main piston *c* until the advancing supplementary piston comes in contact with the cylinder-cover, and the piston *c* then finishes its stroke by itself, as before.

Around the piston-rod *e* is placed a sleeve, *p*, which is secured at one end to the supplementary piston *d*, and provided at its outer end with a stuffing-box, *h'*, and which may be done by attaching any device for producing the proper motion of the pistons *d d'* to the sleeve *p* at the outer end. In this case the friction arrangement *i j k* may be dispensed with in piston *c*.

The operation is as follows: When the pistons are in the position shown in the drawings, the piston *c* moving in the direction of the

arrow, the water in space 1, between the pistons *c d*, is being forced out through the port *m* into the chamber *o*, and thence into the delivery-pipe *n*. At the same time water is being drawn through the port *l* into the space 2, between the pistons *c d'*. When the piston *c* has completed its stroke, the space 2 will be filled with water and space 1 will have been closed. Upon the return-stroke of the piston *c* the supplementary pistons *d d'* and the water in space 2 will be carried forward until the piston *c* passes the port *l* and piston *d'* has passed the edge of the port *m'* and come in contact with the cylinder-cover, when the water in space 2 will be forced out through port *m'* to the delivery-pipe through chamber *o*. While the water is being forced out of the space 2 water is being drawn into the space 1, these spaces 1 and 2 being alternately filled and emptied at each stroke of the piston. It will be seen that no resistance is offered to the movement of the supplementary pistons by the water that is between them and the cylinder-covers, as the chamber *o* being always full of water and communicating with each end of the cylinder by the ports *m m'*, a perfect equilibrium is established.

I have described and shown two supplementary pistons and ejection-ports, but it is evident that only one supplementary piston and one ejection-port may be employed, if desirable. If desired, two or more pumps can be arranged to communicate with the same water-chamber, thereby causing a continuous flow of the liquid.

I do not limit myself to the precise arrange-

ment or proportion of ports and pistons, as these will require to be varied in accordance with the work to be performed and the density of the liquids raised.

What I claim as my invention, and desire to secure by Letters Patent, is—

1. A pump consisting of a cylinder, *a*, having suitable heads, *b b'*, and containing a main piston adapted to have a continuous reciprocating motion, and two supplementary pistons, *d d'*, adapted to have a simultaneous reciprocating motion, said cylinder being provided with suitable ports, substantially as shown and described. 40

2. The combination of the cylinder *a*, heads *b b'*, piston *c*, supplementary valveless pistons *d d'*, connecting-rods *ff*, and piston-rod *e*, all substantially as and for the purpose set forth. 45

3. The combination of the cylinder *a*, heads *b b'*, piston *c*, friction device *i j k*, supplementary pistons *d d'*, connecting-rods *ff*, and piston-rod *e*, substantially as shown and described. 50

4. The combination of the cylinder *a*, heads *b b'*, ports *l m m'*, piston *c*, containing the friction devices, the supplementary pistons *d d'*, rods *ff*, piston-rod *e*, and sleeve *p*, substantially as shown and described. 60

In testimony whereof I have signed my name 65 to this specification in the presence of two subscribing witnesses.

HORACE F. HODGES.
